FIG. 1

FIG. 2.

FIG. 3

FIG. 7

FIG. 4

FIG. 5

FIG. 6

FIG. 1 is a front elevational view showing my design for an adjustable turning and boring head toolholder;

FIG. 2 is a bottom plan view of the toolholder shown in FIG. 1;

FIG. 3 is a top plan view of the toolholder shown in FIG. 1;

FIG. 4 is an elevational view of the toolholder shown in FIG. 1, looking at the toolholder of FIG. 1 from the right;

FIG. 5 is an elevational view of the toolholder shown in FIG. 1, looking at the toolholder of FIG. 1 from the left;

FIG. 6 is a back elevational view, looking at the toolholder as shown in FIG. 4 from the right; and

FIG. 7 is a fragmentary view of a portion of the toolholder looking in the direction of arrows 7-7 of FIG. 2.

The dominant features of the design reside in the portions shown in full lines.

I claim:

The ornamental design for an adjustable turning and boring head toolholder, substantially as shown and described.
